UNITED STATES PATENT OFFICE

WALTER S. FINNELL, OF ELKHART, INDIANA

RECEPTACLE FOR MOPPING MACHINES

Application filed August 8, 1927. Serial No. 211,420.

My invention relates to an improved receptacle embodying a mop supporting shield and drain control, and which is adapted particularly for use in floor mopping machines.

One of the objects of my invention is to provide a simple, inexpensive, highly efficient and readily detachable drain control means for receptacles of this character which is self-closable and which is adapted to drain all of the water (and any dirt therein) from the receptacle quickly and with a minimum of effort on the part of the operator,—the arrangement being such that the possibility of leakage and accidental opening of the drain and accidentally leaving the drain open is eliminated.

Another object is to provide a cheap, lightweight and efficient mop shield in the receptacle to support the mop prior to and during the wringing operation and to keep the same out of the water which may be in the tank, the shield being firmly supported in horizontal position and being so constructed and mounted as to be readily and quickly inserted and removed from the receptacle for cleaning and the like purposes. The shield is also mounted in such a manner that it may be raised and lowered from its normal horizontal position without detachment of the same.

Other and further objects will become apparent as this description progresses and by reference to the accompanying drawings wherein,—

Figure 1 is a perspective view of a mopping machine embodying my invention.

Fig. 2 is an enlarged vertical section taken substantially on line 2—2 of Fig. 3 and clearly illustrating my mop shield and drain control means as applied to a so-called dirty-water receptacle.

Fig. 3 is a plan perspective view (slightly reduced) of the receptacle of Fig. 2.

Fig. 4 is an enlarged partial section taken substantially on the line 4—4 of Fig. 2 and clearly illustrating the construction of one of the mop shield supports and an adjacent part of the shield.

My invention may be used in connection

with various kinds of mopping machinery and in the drawing I have shown it as applied to a portable mop truck 10 mounted on wheels 11 and adapted to support a dirty water receptacle 12 and a clean water receptacle 13. My invention is particularly adapted to the dirty water receptacle and will be described specifically as applied thereto; however, it is to be understood that it, and particularly the drain control means, 55 may be applied to both receptacles and in a like manner. These two receptacles 12 and 13 may be separately constructed and mounted as shown in Fig. 1, or a single receptacle may be employed of desired size 60 and having a partition to divide the same into a dirty water compartment and a clean water compartment.

The dirty-water receptacle 12 is, preferably, but not necessarily, rectangular in 70 shape and is detachably mounted beneath a wringer 14 rigidly supported by the framework 10^a of the truck. In use, the dirty mop may be passed through the wringer 14 in a well known manner to remove the dirty 75 water therefrom, the water passing from the mop into the receptacle beneath. The mop is next rinsed in the clean water tank 13 and again passed through the wringer 14 to finally clean and dry it for further 80 mopping. During the foregoing wringing operation, as is well understood, the wringer rolls are separated and the mop passed therebetween and the wringer again closed 85 and operated to draw the mop between the closed rolls. It is highly desirable, when the wringer 14 is opened and the rinsed mop passed between the rolls, that it be prevented from coming in contact with the dirty water in the receptacle 12. To this end, I 90 provide a shield 15 in the receptacle 12 above the level of the water therein and this shield also serves as a support for the mop prior to the wringing operation. The shield which I employ is preferably, formed of a 95 lightweight piece of sheet metal of a shape approximating the cross-sectional shape of the receptacle and it has its edges spaced from the walls of the receptacle to permit the water from the mop to freely flow there- 100

past into the lower part of the receptacle. It is desirable that the receptacle be cleaned frequently and the shield 15 is mounted for ready and quick removal to assist in this. To this end, I employ, at 5 two opposite sides of the receptacle, flexible metal strips 16 each having one end rigidly secured in any desired manner, preferably as shown in Figs. 2 and 4, to the top edge of the receptacle. Each of these strips is so formed that its other and free end projects downwardly and inwardly of the receptacle. Each strip is provided, at its free end, with an opening 16^a adapted to freely receive the end of a rod 17 which passes through suitable openings 18^a in a downwardly depending flange 18 which extends around the edge of the shield. In this manner the shield is pivotally carried by the strips 16 and it may be readily and quickly 15 disengaged by springing the strips 16 away from the shield toward the adjacent side walls. The shield is rigidly supported in its horizontal mop-supporting position by another metal strip 19 having its one end attached to an opposite side wall of the can in a manner similar to strips 16, and having its other end free and extended downwardly and inwardly with a hook-like part 19^b adapted to receive the adjacent 20 part of the flange 18 of the shield. This strip 19 may be pressed or sprung inwardly against the adjacent wall to permit the shield to be swung about its pivot rod 17 to a raised or lowered position. Furthermore, this form of strap support readily 25 permits of spacing of the shield edge from the receptacle walls.

It is desirable that the water, together 30 with sediment and dirt therein, be drained from the receptacle from time to time. With faucets or other drain outlets previously located in the side walls of such receptacles, all of the water and dirt in the can could not be readily drained and there was the possibility of the drains being accidentally opened or being accidentally left in opened position whereby the water would flow upon and soil the already 35 cleaned floor surface. My invention eliminates all of these objectionable features as follows:

The drain outlet 20 located in the bottom of the receptacle and large enough to 40 quickly and completely drain the same is adapted to be closed by a rubber wedge-shaped rubber plug 21 which is rigidly, but detachably, secured to an operating rod 22 as by a nut and threaded connection 23. The rod 22 is supported and guided by sheet 45 metal triangularly-shaped guides 24 having upturned flanges 24^a attached to the walls of the can as illustrated in Figs. 2 and 3, these guides being provided with suitable 50 openings 24^b to freely receive the rod. The

upper end of the rod 22 is provided with a handle extension 25 which permits the same to be readily grasped and reciprocated by the operator. All of this drain control structure is located within the receptacle 70 and the parts are so arranged that the drain will not be accidentally opened.

To render the plug self-closable and to prevent the operator accidentally leaving the drain open, I interpose a spring 26 between the lower guide 24 and a suitable stop 27 fixed upon the rod which is normally under compression forcing and holding the plug 21 in a tight seated position in the drain 20. The drain may be opened by 75 vertical movement of the rod 22 and it will be automatically closed by the spring 26 upon release of the handle 25 by the operator. The water acting upon the top of the plug 21 will assist the spring 26 in 80 holding the same closed.

Although I have shown and described only one form of my invention, I do not desire to be limited to that specific form because it is obvious that various changes 90 and modifications may be made therein without departing from the spirit and scope of my invention as defined by the claims which follow.

I claim:

1. In a receptacle for mopping apparatus, a mop shield; and means for supporting said shield in horizontal position in and spaced from the walls of said receptacle, including flexible straps suspended from opposite walls of the receptacle and having their free ends extending downwardly and angularly away from said walls, and means carried by said shield engaging the free end of said straps for supporting one shield edge, 100 and means for supporting another edge surface of said shield, the shield being readily disconnected by springing said straps away from said shield toward said walls.

2. In a receptacle for mopping apparatus, 110 a flat mop shield having a depending flange around its edge; and means for supporting said shield in horizontal position spaced from the walls of said receptacle comprising flexible straps suspended from opposite 115 side walls of the receptacle and extending downwardly and angularly away from said walls, a hinge rod carried by the flange of said shield and engaging the free ends of said flexible straps, and another strap depending from another wall of the receptacle and having a hooked end portion which receives the adjacent part of said shield flange.

3. In a mopping machine receptacle, a horizontally disposed shield in the receptacle 125 for supporting a mop and for keeping it from contact with water therein, said shield being spaced from the walls of the receptacle to permit water to pass freely thereby, and means carried by said receptacle for support- 130

ing said shield in horizontal position including members having attaching portions engaging opposite sides of said shield, said attaching portions permitting said shield to be swung upwardly and downwardly when released from at least one of said members.

4. In a mopping machine receptacle, a horizontally disposed shield in the receptacle for supporting a mop and keeping it from contact with water therein, said shield being spaced from the walls of the receptacle to permit water to pass freely thereby, means carried by said receptacle walls for swingably supporting one edge of said shield permitting it to be swung upwardly and downwardly, said means being also yieldable toward the adjacent receptacle wall to permit the same to be disengaged from said shield for removal of the shield from the receptacle, and additional means carried by said receptacle for supporting an opposite edge of said shield to hold the shield in a horizontal position.

5. In a mopping machine receptacle, a horizontally disposed shield in the receptacle for supporting a mop and for keeping it from contact with the water therein, said shield being spaced from the walls of the receptacle to permit water to pass freely thereby, straps carried by and extending downwardly and away from opposite walls of the receptacle, a pivotal connection between said straps and said shield, another strap carried by another wall of the receptacle for supporting another part of said shield to position it in horizontal position.

6. In a mopping machine, the combination with a water receptacle having an outlet in its bottom wall, of a horizontally-disposed mop rest within and spaced from the walls of the receptacle, a valve for controlling said outlet, a handled operating rod for said valve extending past said rest to a point convenient to the operator, but disposed wholly within said receptacle, supporting means for said valve rod, said rest being cut away at one edge to accommodate said rod and support and to permit water to pass freely therebetween, and means acting on said rod and opposing opening movement of said valve and rendering it self-closable when said handle is released.

7. In a mopping machine, a receptacle having a flat mop shield therein, a hinge connection including a yieldable element between the shield and the receptacle at one end of said shield, said element being adapted for lateral movement to disengage said shield and receptacle, and a displaceable support on the receptacle for receiving an opposite edge of said rest for positioning it in a horizontal position.

8. In a receptacle for mopping apparatus, a mop shield, a plurality of supports suspended from the walls of the receptacle each

having its lower end spaced inwardly away from such walls, the edges of said shield being detachably supported by said supports, and the number and position of said supports being such as to hold said shield in a horizontal position spaced from the walls of the receptacle.

9. In a receptacle for mopping apparatus, a mop shield, a plurality of supports suspended from the walls of said receptacle with their lower ends spaced inwardly from such walls, said shield being mounted upon said supports with its edges spaced from the receptacle walls, said supports being movable away from said shield to detach the shield, and the number of said supports being sufficient to carry said shield in a horizontal position.

10. In a receptacle for mopping apparatus, a mop shield, a plurality of supports suspended from the walls of the receptacle with their lower ends spaced inwardly away from such walls, said shield being mounted upon said supports with its edges spaced from the receptacle walls, the mounting between two of said supports and said shield providing for hinging movement of the shield.

11. In a receptacle for mopping apparatus, a mop shield adapted to be carried horizontally within the receptacle, support members carried by the upper part of said receptacle walls extending within the receptacle adjacent said shield, the lower ends of said supports and adjacent edges of said shield being constructed for detachable engagement with each other.

12. In a receptacle for mopping apparatus, a mop shield mounted within the receptacle, and means for supporting said shield horizontally with spacing between its edges and receptacle walls which includes spaced members having one end supported from the receptacle and the other end free, the free ends of said members and opposite sides of said shield being formed for detachable support engagement.

13. In a mopping apparatus receptacle, a mop shield disposed within the receptacle, shield support members carried by said receptacle walls and extending toward opposite sides of said shield with one end of each free for engagement with said shield, opposite sides of said shield having attaching portions for detachably engaging said supports to support said shield in horizontal suspended position.

In testimony whereof, I have subscribed my name.

WALTER S. FINNELL.
